DOUBLE BREASTED COAT

Jerome Giuseffi, Cincinnati, Ohio, assignor to
The Goodall Worsted Company, Sanford,
Maine, a corporation of Maine

Application November 6, 1941, Serial No. 418,059

4 Claims. (Cl. 2—96)

This invention relates to double breasted coats and other garments in which the underlying section (in men's coats, the right side) is carried across and buttoned to the inside of the overlying section of the garment. Heretofore, and as commonly practiced at the present time, this underlying front section is fastened to a button secured to the inside of the overlying coat section, said button being secured opposite and in registry with one of the outer front buttons of the overlying coat section. The positioning of the opposed buttons in this way has been generally recognized as undesirable since in a high percentage of cases one or the other, or both, of the juxtaposed buttons are broken when the coat is cleaned and pressed, and moreover, the cleaning and pressing operation is rendered more difficult because of the obstruction of the two buttons sewed together in the manner described.

The object of the present invention is to eliminate these difficulties and to attain other advantages, and the invention consists, briefly, in securing to the inside of the front section of the coat, a small flap, cord, extension or the like having a button secured thereto and to which button the opposite or underlying section of the coat is attached in wearing position and at which time the button on said flap falls into substantially the same vertical line as the buttons on the outer face of the overlying section of the coat. When the coat is to be cleaned or pressed, the flap is simply turned in the opposite direction, at which time its button is brought well out of registration with the adjacent button on the face of the overlying coat section so that the buttons are not broken during the cleaning and pressing operation nor do they provide the considerable obstruction or hump that inevitably results when the buttons in question are positioned in accordance with present practice.

In more detail and with reference to the drawing:

Fig. 1 is a front view of a man's double breasted coat with the right or underlying front section of the coat shown in wearing position and with the left, or overlying section, of the coat thrown back to reveal the invention as applied to the inside of said section.

Fig. 2 is a cross-sectional view through those portions of the coat (in operative position) to which the invention has been applied.

The coat may comprise the underlying front section 5 comprising the outer thickness 6 and the inner facing 7. The coat section 5 may be suitably lined, as indicated at 8, and is provided

with a buttonhole 9 which cooperates with the button means on the opposite coat section, to be described.

This opposite or overlying section of the coat, 5, designated at 10, may likewise comprise inner and outer members 11 and 12 and lining 13 whose connecting seam is shown at 14. Outer buttons on the face of this overlying section of the coat are indicated at 15.

10 In accordance with this invention a short flap or extension piece 16 has one end secured to the inner side of the overlying coat section 10. The connection is preferably made at the seam 14, as indicated at 17. The flap 16 has a button 18 secured adjacent its free end and, when the coat is placed in wearing position, this button is adapted to be engaged with the buttonhole 9 of the opposite or underlying section of the coat. The flap 16 is so positioned that, when the coat is thus in place, the button 18 of said flap falls substantially into alignment with that button 15 on the outer face of the section 10 with which it would be connected, in accordance with present general use.

25 The underlying section of the coat is thus properly held in wearing position and the fastening of the two sections of the coat together is accomplished more easily and with less handling and crumpling of the adjacent parts of the suit.

30 In addition, the structure of this invention facilitates access to the wearer's trouser pockets since it permits the overlying or left section of the coat front to be unbuttoned and turned back to a greater extent than heretofore, and without 35 the necessity of unfastening the underlying section of the coat attached to the said flap button.

When the coat is to be cleaned, the flap 16 is simply turned in a direction away from the front line of buttons on the face of the overlying coat section, as seen in dotted lines (Fig. 2), whereby 40 the objectionable obstruction or hump, already referred to, in coat construction as now known, is obviated, since the flap button and the adjacent one on the outer face of the coat are completely disassociated whereby pressing and cleaning may be readily accomplished and without danger of breakage of the buttons.

What is claimed is:

1. In a double breasted coat, a flap secured to the inside of the overlying section of the coat front, and a button on the flap adapted to engage the underlying section of the coat front for holding said underlying section in proper wearing position.
2. A double breasted coat or garment provided

with buttons and buttonholes on both sections or sides of the coat front, a small flap or the like secured to the inside of the overlying or top section of the coat front, and a button on said flap adapted to engage the underlying section of the front of the coat when the latter is in position for wearing, said flap being secured at such point that its button, when the coat is in wearing position, falls substantially in line with the buttons on the outer side of the overlying coat section but in non-registration with any one of said buttons.

3. A double breasted coat or garment provided with the buttons and buttonholes on both sections or sides of the coat front, and a small flap or the like secured to the inside of the overlying or top section of the coat front, said flap being positioned beneath one of the buttons of said

overlying coat section and having a button attached thereto for engaging the underlying section of the coat front, said flap being adapted in use to extend toward the opposite section of the coat front at which time said flap button lies substantially beneath an outer button on the coat, and said flap, when the coat is to be pressed or cleaned, being adapted to be extended in the opposite direction for bringing its button out of alignment with said outer button.

4. In a double breasted coat, a flap secured to the inside of the overlying section of the coat front, and means on the flap adapted to engage the underlying section of the coat front for holding said underlying section in proper wearing position.
